UNITED STATES PATENT OFFICE.

OTTO C. KNIGGE, OF NEW YORK, N. Y.

REFUSE-COLLECTING TRUCK.

1,324,675.

Specification of Letters Patent.

Patented Dec. 9, 1919.

Application filed February 26, 1919. Serial No. 279,465.

To all whom it may concern:

Be it known that I, OTTO CHARLES KNIGGE, a citizen of the United States, and a resident of the city of New York, borough of Manhattan, in the county and State of New York, have invented a new and Improved Refuse-Collecting Truck, of which the following is a full, clear, and exact description.

10 The present invention relates to improvements in wagons or trucks especially adapted for collecting ashes, garbage, or the like.

A principal object of the invention is to provide a device of this character in which 15 suitable containers carrying the material collected, may be elevated to the top of a wagon or truck and dumped therein.

A further object of the invention is to provide means for dumping the containers.

20 A further object of the invention is to provide means for simultaneously dumping a plurality of containers.

A further object of the invention is to construct the dumping means that the receptacles are automatically returned to the 25 filling position.

A further object of the invention is to provide a loading device in which the several containers may be dispensed with if 30 desired.

A further object of the present invention is to provide a device in which the container-dumping mechanism may be folded out of the way when the same is not in operation.

35 Reference is to be had to the accompanying drawings forming a part of this specification, in which like characters of reference indicate corresponding parts in all the views, and in which—

40 Figure 1 is a side elevation of a truck constructed in accordance with the present invention;

Fig. 2 is a transverse vertical sectional view on the line 2—2 of Fig. 1;

45 Fig. 3 is a detail sectional view;

Fig. 4 is a side elevation partly in section of a modified form.

Referring more particularly to the drawings, the reference character 10 designates 50 the chassis or frame of the truck. Carried by said chassis on opposite sides thereof is a trackway 11, in which engages a roller bracket 12, which forms means by which the truck may be dumped. Extending transversely of the truck body and supported on

the top face of the trackway 11, are I-beams 13. These I-beams serve to support the body proper 14 of the truck, which is preferably formed of sheet metal, said body being secured to the I-beams 13. 60

Secured to the body 14 at each end thereof, is a substantially inverted U-shaped member 15, which is constructed of channel iron. This U-shaped member 15 is formed with the channel side outward, to provide a trackway 16, the purpose of which will be hereinafter described. Connecting the upper portions of these inverted U-shaped members 15, and extending longitudinally of the body 14, is a rod 17, which serves as a means 70 to brace the inverted U-shaped members 15 and retain the same in proper spaced relation. As shown in Figs. 1 and 2, the legs of the U-shaped members 15 project downwardly below the chassis 10 of the truck, 75 shown at 18, to a point in close proximity to the ground.

Each of these U-shaped members has its legs connected by a strip 19, and pivotally secured centrally of said strip, as at 20, 80 is a bail-like member 21, which is adapted to swing about the pivot 20. The body portion 22 of the bail-like member 21, is positioned in such a manner that it passes around the U-shaped members 15, as shown 85 in Figs. 1 and 2. Connected to the body portion 22 of the bail-like member 21, by means of a hook 23, or the like, is a cable 24, which cable passes through a pulley 25 mounted on the rod 17. From the pulley 25, 90 the cable leads to pulleys 26 and 27 mounted at the top and bottom, respectively, of one of the sides of the body 14, and from the pulley 27, the cable 24 leads around a pulley 28 on the bottom face of the body 14. 95 From the pulley 28, the cable 24 leads over the pulleys 29 and 30, to a convenient form of hoisting mechanism 31. By this arrangement, it will be seen that the hoisting mechanism 31 is operated, and the bail-like member 21 will be moved about its pivot 20 to the position shown by dotted lines in Fig. 2. 100

Extending longitudinally of the body of the truck on the exterior thereof, is a trough or like member, 32, which consists of a rear wall 33, to which is hinged a latch member 34; a bottom 35, and a front wall 36. The latch member 34 is provided with a catch 37, which is adapted to engage in the opening 38 in the front wall, in which position it 110

serves to maintain the trough 32 in its extended position, and, at the same time, provides a means for retaining a plurality of refuse receptacles 39 in position in said trough.

Carried by the outer face of the rear wall 33, at each end thereof, is a roller 40, which is adapted to travel within the tracks of the U-shaped members 15. Connected to the bearings 41 in which said rollers 40 are mounted, is a chain 42. The other end of the chain 42 is secured at 43 to the body portion 22 of the bail-like member 21.

Secured to the rear wall at each end thereof, of near its top, is a guide member 44, which is adapted to engage behind the legs of the U-shaped members 15, as shown in Figs. 2 and 3, thus preventing the trough 32 from tipping outwardly away from the body 14.

By this arrangement, it will be seen that when the bail-like member 21 is moved to the dotted-line position shown in Fig. 2, through the medium of the cable 24 and the hoisting mechanism 31, the trough 32 will be moved upwardly over the top of the inverted U-shaped members 15 and when it reaches the point shown by dotted lines in Fig. 2, the trough 32 rocks about the pivot 45 formed by the rollers 40 and the bearings 41, to the dumping position shown in Fig. 2. In this position, it will be apparent that the refuse receptacles 39 are free to deposit their contents within the body 14 of the truck, and that through the medium of the latch members 34, each of the refuse receptacles 39 is prevented from becoming displaced in the trough 32.

If after this operation has been completed, the cable 24 is slackened off, the trough 32, together with the refuse receptacles 39, are automatically returned to the position shown in full lines in Fig. 2 for the further reception of refuse.

While I have shown refuse receptacles 39, it is, of course, to be understood that the trough 32 may be used without these receptacles 39, since the refuse may be deposited directly in said trough, from which it is free to be dumped upon operation of said trough as hereinbefore described.

In Fig. 3, the trough 32 is shown folded, which position it occupies when not in use. To provide for this feature in the construction of the device, the bottom wall 35 of the trough is pivoted to the rear wall 33 thereof, as at 46, the front wall 36 of the trough being pivoted to the bottom wall at 47. The bottom wall 35 is adapted to be folded into parallel relation with the rear wall 33, the front wall 36 lying between the two. With the parts in this position, the latch member 34, which is pivoted as at 48, to the upper edge of the rear wall 33, is adapted to be swung over into engagement with the bottom wall 35 of the trough and serves

through the medium of its leverage to retain the parts in their folded position.

In the modified form of the invention shown in Fig. 4, the rod 17 which extends between the two U-shaped members is removed, and connected to the bail member 21 near each end thereof is a cable 49. These cables extend around the U-shaped members 15, and each is wound upon a drum 50, which drums are carried by a shaft 51. This shaft 51 is suitably supported as by brackets 52, and extends longitudinally of the body of the truck. The front end of the shaft is projected slightly beyond the forward U-shaped member 15, as at 53, and is provided with a bevel gear 54. This bevel gear 54 meshes with a bevel gear 55 carried upon a short shaft 56 mounted in a suitable bracket 57. Carried by the lower end of the shaft 56, is a bevel gear 58 which in turn meshes with a bevel gear 59 mounted on the rear end of a shaft 60. This shaft 60 is adapted to be driven at any desired speed by means of the engine of the motor vehicle, or by connecting the same to any one of the several speeds of the transmission gearing, which is conveniently shown at 61 in said figure.

In this form of the invention, when the shaft 60 is rotated, it will be seen that through the medium of the bevel gears 54, 55, 58 and 59, the shaft 51 will be rotated, thus rotating the drums 50 and causing the cables 49 to be wound thereon to elevate the receptacle-supporting trough 32.

From the foregoing, it will be seen that when the trough 32 is not in use, the same may be folded in such a manner that it will not interfere with proper operation of the truck through the traffic of crowded streets.

Having thus described the invention, what is claimed is:

1. A device for loading vehicles comprising an inverted U-shaped member secured to the body at each end thereof and forming tracks; a pivoted member adapted to move over said track on the exterior surface thereof; a trough; a roller carried by each end of the trough and movable in said tracks, a guide member carried by each end of the trough and engaging said tracks to guide the trough in its movement thereover; means for moving the pivoted member with respect to the tracks; and means connecting the pivoted member and the trough for moving the trough to dumping position upon movement of the pivoted member.

2. A device for loading vehicles comprising a pair of tracks located one at each end of the vehicle body, a bail movable over said tracks, a trough extending parallel to the wagon body and arranged on the side thereof, means connecting said trough at its ends to said bail, said connecting means lying in said tracks and being movable longitudi-

nally thereof, and means for operating the bail about its pivotal points and to move the trough to its dumping position through the medium of said connecting means.

- 5 3. A device of the character described, comprising in combination with a wagon body, a bail pivotally connected to the ends of said body, a pair of tracks rigidly carried by said body, a trough movable over said 10 tracks from loading position to dumping position, means connected to said bail and to said trough for moving the trough over

said tracks, and means for operating said bail.

4. In combination with a wagon body 15 having a curved track at each end thereof, a trough movable over said tracks, means for moving said trough over said tracks, and means carried by said trough and adapted to engage said tracks to maintain the trough 20 in position for loading, and to automatically disengage said tracks to permit of the dumping of said trough.

OTTO C. KNIGGE.
